UNITED STATES PATENT OFFICE.

RAYMOND L. JEWELL, OF MILLCREEK TOWNSHIP, ERIE COUNTY, PENNSYLVANIA, AS
SIGNOR TO AMERICAN STERILIZER COMPANY, OF ERIE, PENNSYLVANIA, A COR-
PORATION OF PENNSYLVANIA.

DOOR-CLOSING APPARATUS.

Application filed November 25, 1925. Serial No. 71,479.

The invention is designed to improve door closure apparatus for such doors as are used for pressure containing vessels, such as sterilizers, vulcanizers and the like. It is particularly directed to the improvement of door closures utilizing radially acting levers which levers are moved in and out of position by a rotative movement of their inner ends and are moved axially at their inner ends to exert closing pressure on the door. Such devices as heretofore made comprise a head carrying the inner ends of the levers and this has been frictionally connected with the nut moving the inner ends of the levers axially. The frictional engagement has swung the inner ends of the levers radially to move the outer ends of the levers to their setting position and the continued action of the nut against the friction accomplishing the axial movement. With this structure, therefore, the operator must overcome the friction in the continued action of the nut, or if the friction is made comparatively light the movement of the levers is rendered uncertain. With the present device this preliminary rotating movement of the levers is positively performed automatically as the nut is rotated with the preliminary movement and the release takes place in a like manner. Thus there is a certainty of operation of the levers and the operation of the nut is relieved of the frictional resistance. Features and details of the invention will appear from the specification and claims.

The invention is illustrated in the accompanying drawings as follows:

Fig. 1 shows a section on the line 1—1 in Fig. 2.

Fig. 2 a front elevation of the door partly in section on the line 2—2 in Figure 1.

Fig. 3 a central section of the locking mechanism on the lines 3—3 in Figs. 1 and 2.

Fig. 4 is a detail of the operating head.

1 marks the sterilizer chamber walls, 2 the head on the wall, 3 the door seating in the annular seat 4 of the head. The head is provided with an annular hook 5 which engages the ends of the pressure exerting levers 6. These levers are fulcrumed on a ring

7 on the head and secured in place by straps 9, the straps being secured to the ring 7 by screws 9^a, the screws extending into round posts 9^b on the ring 7 affording clearance for the angular movement of the fulcrum levers as they are moved into and out of position under the hook as hereinafter described.

The door may be moved to and from its seat by any convenient mechanism ordinarily involving a hinge (not shown).

The levers 6 have spherical inner ends 6^a and these are arranged in bearing sockets in a head 10, the head being formed in two parts secured together by pins 10^a. The head 10 is rotatively mounted on a nut 11, the nut being provided with radially arranged handles 12. The nut is screwed on to a post 13 extending from the door and having a screw-threaded end 14.

The nut is provided with a series of notches 15 around its periphery adapted to receive a latch 16. The latch is pivotally mounted on a pin 17 between fingers 18. The fingers 18 extend inwardly from the head 10. The outer end of the latch is yieldingly forced inwardly by the action of a spring 19 operating on the opposite end of the latch, the spring being anchored on a bridge plate 20 joining the fingers 18 on the head 10.

A cam plate 21 is mounted on the door. This is provided with an annular cam 22 which is adapted to engage the inner end of the latch 16 with the levers approximately in their final, or radial position, as shown in Fig. 2 and with the nut retracted so as to lift the latch above the retarding ring 24 as hereinafter described (see Fig. 2). The latch is limited in its movement in a reverse direction by a stop 21^a on the plate 21. When swung to this position the levers 6 will be drawn out of the true radial position toward a tangent to their socket connection and will thus be withdrawn from the hook 5.

The operation of this part of the mechanism is as follows: Starting with the latch 95 against the stop 21^a the door is put in place, the nut is turned in a direction to set the levers. The latch being in the notches 15

the head 10 is locked with the nut as clearly indicated in Figs. 2 and 3 and consequently the inner ends of the levers are swung rotatively moving the outer ends of the levers outwardly under the hooked flange 5. As the latch reaches the cam 22 the further movement of the nut with the latch forces the inner end of the latch inwardly and the outer end of the latch 16 outwardly to clear the walls of the notches 15. The nut is then screwed in by turning the handles 12 and as it is screwed in it forces the outer ends of the levers 6 inwardly and the outer ends of the levers outwardly against the hook 5 sealing the door.

The movement of the latch after the engagement with the cam 22 carries the inner ends of the levers 6 slightly beyond the desired position and as the nut forces the head 10 inwardly it carries with it the fingers 18. One side of the finger engages a cam 23 extending outwardly from the plate 21 which forcibly rocks the head 10 in a reverse direction so as to finally position the levers in their radial or desired position. This positioning of the latch mechanism through the fingers 18 on the cam 23 is desirable so that as the nut is screwed outwardly in releasing the door carrying with it the head and latch 16 the latch will be in position when the nut has reached a release position as shown in Fig. 3 to permit the inner end of the latch 16 to swing over the retarding ring 24. It will be understood that as the head moves inwardly the inner end of the latch is in engagement with the retarding shoulder 24 so as to lock the latch 16 out of the notch 15 until the nut is again brought outwardly to the position shown in Fig. 2 so that with the initial return movement of the nut the latch is held out of the notches 15 until the nut has moved outwardly a sufficient distance to bring the levers to a position releasing pressure on the door and the flange 5. At this point the latch snaps off of the ring 24 and picks up the first notch as it passes with the nut and swings the head 10 in a return direction until the stop 21^a is reached. This return swinging of the head swings the inner ends of the levers rotatively and draws the outer ends of the levers inwardly to clear the flange 5.

What I claim as new is:

1. In a door closure apparatus, the combination of a door; a lever pressure system on the door comprising a rotative lever actuating head; a post on which the head is mounted; a nut screwed on the post actuating the head; and devices positively locking the head with the nut to swing the levers.
2. In a door closure apparatus, the combination of a door; a lever pressure system on the door comprising a rotative lever actuating head; a post on which the head is mounted; a nut screwed on the post actuating

ing the head; devices positively locking the head with the nut to swing the levers; and means releasing said devices permitting the continued movement of the nut to set the levers.

3. In a door closure apparatus, the combination of a door; a lever pressure system on the door comprising a rotative lever actuating head; a post on which the head is mounted; a nut screwed on the post actuating the head; devices positively locking the head with the nut to swing the levers; and means automatically releasing said devices permitting the continued movement of the nut to set the levers.

4. In a door closure apparatus, the combination of a door; a lever pressure system on the door comprising a rotative lever actuating head; a post on which the head is mounted; a nut screwed on the post actuating the head; devices positively locking the head with the nut to swing the levers; and means actuated through the turning of the nut automatically releasing said devices permitting the continued movement of the nut to set the levers.

5. In a door closure apparatus, the combination of a door; a lever pressure system on the door comprising a rotative lever actuating head; a post on which the head is mounted; a nut screwed on the post actuating the head; and devices comprising a latch mounted on the head positively locking the head with the nut to swing the levers, and a cam on the door acting on the latch to release the same with the turning of the head.

6. In a door closure apparatus, the combination of a door; a lever pressure system on the door comprising a rotative lever actuating head; a post on which the head is mounted; a nut screwed on the post actuating the head; devices positively locking the head with the nut to swing the levers; means automatically releasing said devices permitting the continued movement of the nut to set the levers; and mechanism retarding the re-locking of the devices on the return movement of the nut.

7. In a door closure apparatus, the combination of a door; a lever pressure system on the door comprising a rotative lever actuating head; a post on which the head is mounted; a nut screwed on the post actuating the head; devices comprising a latch mounted on the head positively locking the head with the nut to swing the levers, and a cam on the door acting on the latch to release the same with the turning of the head; and means returning the head to position the levers as the nut advances.

8. In a door closure apparatus, the combination of a door; a lever pressure system on the door comprising a rotative lever actuating head; a post on which the head is

mounted; a nut screwed on the post actuating the head; and devices positively locking the head with the nut to swing the levers comprising a latch mounted on the head and locked with the nut, a cam mechanism mounted on the door moving the latch out of engagement with a rotative movement of the head, said cam mechanism having a re-

tarding ring into which the latch is moved as the nut advances, and a cam operating ¹⁰ on the head moving the head in a return direction as it is advanced under the influence of the nut.

In testimony whereof I have hereunto set my hand.

RAYMOND L. JEWELL.
